CAR PORT OR THE LIKE

Henry A. Hinsch, Dallas, Tex.

Application March 26, 1957, Serial No. 45,434

Term of patent 14 years

(Cl. D13—1)

Fig. 1

Fig. 2

Fig. 3

Figure 1 is a perspective view in elevation of the car port or the like, taken from slightly above the roof showing my new design;

Figure 2 is a perspective view similar to Figure 1 taken from the opposite side and slightly below the roof line; and,

Figure 3 is an enlarged fragmentary view of a section of the roof.

The characteristic features of my design for the car port disclosed reside in the roof portions having the configuration shown.

I claim:

The ornamental design for a car port or the like, substantially as shown and described.
